UNITED STATES PATENT OFFICE.

HENRY E. J. WACKWITZ, OF PORT WASHINGTON, NEW YORK, ASSIGNOR OF ONE-HALF
TO H. R. SMITH, OF PORT WASHINGTON, NEW YORK.

PAINT-BRUSH.

1,277,508.

Specification of Letters Patent. Patented Sept. 3, 1918.

Application filed February 16, 1918. Serial No. 217,722.

To all whom it may concern:

Be it known that I, HENRY E. J. WACKWITZ, a citizen of the United States of America, residing at Port Washington, L. I., New York State, have invented a new and useful Paint-Brush, of which the following is a specification.

My invention relates to paint brushes and the objects of the invention are to preserve the bristles of the paint brush in good order and particularly to prevent the curling of the bristles.

It has been found that when paint brushes are allowed to stand for a certain length of time the bristles assume a permanent curl and this renders the brush unsatisfactory and in some cases actually useless, long before the brush has been worn out.

In my invention I have overcome and guarded against this curling tendency of the bristles by providing means separate from and independent of the bristles for supporting the brush in a standing position. This supplementary support is preferably in the nature of a foot normally housed in the handle at the base of the bristles and adapted to be projected when the brush is to be laid aside, to a position where it will bear upon the support and take the weight of the brush off the bristles. Conveniently operable means are preferably mounted on the handle for projecting and retracting this support at will.

In the accompanying drawing I have illustrated the invention made in several practical forms but at the same time I would have it understood that further changes and modification may be made without departure from the true spirit and scope of the invention.

In said drawing:—

Figure 1, is a partial sectional view of a paint brush having my invention incorporated therein.

Fig. 2 is another sectional view taken at right angles to the plane of Fig. 1.

Figs. 3 and 4 are broken detail views showing a modified construction of operating device for projecting and retracting the supporting element.

Figs. 5 and 6 are broken detail views of a combing type of brush support.

The brush illustrated is of typical construction in that it embodies a handle portion 5 and a body of bristles 6 attached thereto. This handle however is of hollow

construction having a chamber 7 formed in the head portion thereof, at the base of the bristles and a passage 8 extending therefrom, longitudinally of the handle. 60

The supplementary support consists in the present disclosure of a foot member 9 carried by a rod or stem 10. The rod slides within the passage 8 in the handle and the foot portion of the support is adapted to be 65 housed when not in use within the chamber 7. This so-called foot portion 9 is shown as a relatively flat plate disposed edgewise of the bristles, extending across the width of the brush and having dependent feet 11 70 for engagement with the supporting surface, as indicated in dotted lines in Fig. 1.

Various means may be provided for operating the support. In Figs. 1 and 2 I have shown a finger wheel 12 provided for 75 this purpose, the same being pivotally mounted at 13 on one side of the handle adjacent the lower or head portion thereof, said wheel being toothed as indicated to serve as a pinion engaging a correspond- 80

ingly toothed portion 14 on the adjacent side of the stem of the support. In this form of construction, the hollow handle is entirely closed except at the point where the rim of the finger pinion projects through into engagement with the rack on the stem. The finger wheel may be made of small diameter and may be set down in the handle so as to not interfere or be in the way in the ordinary usage of the brush. When through 90

painting with this construction of brush, the finger wheel is simply operated by the thumb to project the support and the brush is then put away as usual in a bucket of water, oil or the like for keeping the bristles soft and 95

said support, resting as it does upon the bottom of the container, takes the weight of the brush off the bristles so that said bristles can hang straight and free. In addition to preventing the bristles from curling, this 100

method of supporting the bristles also keeps the brush cleaner by allowing the bristles to free themselves of particles of paint, etc. Another advantageous feature of the invention is that in case of caking of the paint in 105 the base portion of the bristles this caking tendency can be overcome by simply projecting and retracting the supporting element so as to break up any clots or hardened substance. When the foot portion of the support is made relatively wide it serves also as a scraper for cleaning the bristles. The 110

- support is preferably made of brass, aluminum, or other non-corrosive material so as to not be affected by paint, etc.
- Another form of operating mechanism is illustrated in Figs. 3 and 4 wherein there is shown a thumb screw 15 for engagement with the stem of the retractable support which in this case is threaded for engagement by said screw as indicated at 16. This thumb screw may be seated in a socket 17 provided therefor in the brush handle so as to be out of the way and at the same time readily accessible for easy operation.

The invention is simple and so inexpensive that it may be readily incorporated in a brush without adding very materially to the cost of the brush and the possible increase in cost is more than off-set by the improved condition in which the brush is kept, and by the period of usefulness thus added to the brush.

The brush supporting blade may also be caused to serve as a comb for combing the bristles by providing it with comb teeth 18 on the opposite edges thereof as indicated in Figs. 5 and 6. Also the upper edge of the blade may be sharpened somewhat as indicated at 19 so as to properly separate the bristles on the retracting movement.

This comb type of support is shown as made up of a single piece of sheet metal or flat blade folded to present a relatively sharp upper edge and having somewhat flaring sides toothed or notched to provide the combing function and also provide supporting feet for engagement with the supporting surface. This comb serves to preserve the bristles in proper relation and is very effective in keeping the bristles properly cleaned.

I claim:

1. A paint brush comprising a handle and a body of bristles carried thereby, said handle having a chamber at the base of the

bristles and a passage extending from said chamber longitudinally of the handle, a brush supporting member adapted to be housed in said chamber and provided with an operating stem extensible into the passage in the handle, and a finger wheel journaled on the brush handle and engaging the stem of the support for retracting or projecting the same.

2. A paint brush comprising a hollow handle and a body of bristles carried thereby, an operating stem inclosed within and slidably guided in said hollow handle, a brush supporting member on the end of said stem and adapted to be housed within the hollow handle when the stem is in retracted position, and a manually operable member on the handle connected with the stem within the hollow handle for projecting and retracting the stem and the brush support carried thereby.

3. In combination, a paint brush having a hollow handle and a body of bristles carried thereby, a stem slidably guided in said hollow handle, a plate carried by the end of said stem and adapted to traverse the intermediate portion of the body of bristles as the stem is reciprocated, supporting feet portions on said plate and means for shifting the stem to thereby project and retract the plate.

4. In combination with a paint brush, having a hollow handle, a supporting blade normally housed at the base of the bristles and provided with supporting feet in the form of comb teeth for engagement with the bristles, said supporting blade having a stem projecting into the hollow handle of the brush and inclosed therein and means on the handle engaged with said stem for projecting and retracting said comb blade longitudinally of the bristles.

HENRY E. J. WACKWITZ.
